Hildred C. Felts and Luther T. Bosserman,
Tampa, Fla.

Application March 18, 1949, Serial No. 1,482

Term of patent 14 years

(Cl. D58—12.6)

To all whom it may concern:

Be it known that we, Hildred C. Felts and Luther T. Bosserman, citizens of the United States of America, residing at Tampa, county of Hillsborough, and State of Florida, have invented a new, original, and ornamental Design for a Fishing Tackle Box, of which the following is a specification, reference being had to the accompanying drawings, forming a part thereof, wherein:

Figure 1 is a perspective view of a fishing tackle box with its lid and tray in opened position, showing our new design;

We claim:

The ornamental design for a fishing tackle box, as shown.

HILDRED C. FELTS.
